UNITED STATES PATENT OFFICE.

MINNIE M. MELDRAM, OF NEW YORK, N. Y.

DOLL AND METHOD OF MAKING SAME.

1,362,727.

Specification of Letters Patent. Patented Dec. 21, 1920.

Application filed October 4, 1919. Serial No. 328,351.

To all whom it may concern:

Be it known that I, MINNIE M. MELDRAM, a citizen of the United States, residing at New York, in the county of New York and 5 State of New York, have invented certain new and useful Improvements in Dolls and Methods of Making Same, of which the following is a specification.

This invention relates to improvements in 10 dolls and has as its general object a doll of a novel and improved construction, and a novel method whereby the doll may be manufactured at a low cost.

More specifically it is the object of the 15 present invention to provide a doll the body and apparel of which may be readily and cheaply manufactured from a pair of socks.

Another object of the invention is to devise a method whereby a pair of socks, from 20 which the doll is to be manufactured, may be cut into the required blanks with a minimum of waste of material and so as to eliminate as far as possible the operation of stitching in the manufacture of the doll so 25 as to economize both in time and labor.

In the accompanying drawings:

Figure 1 is a vertical transverse sectional view through the body of a doll constructed in accordance with the present invention;

30 Fig. 2 is a view in front elevation of the body before the application thereto of the upper limb members and apparel;

Fig. 3 is a view partly in elevation and partly in section illustrating the upper limb members about to be assembled with the body, the view illustrating one article of apparel upon the body in section, and other articles of apparel in position about to be assembled with the body;

40 Fig. 4 is a front elevation of the completed doll;

Fig. 5 is a sectional perspective view illustrating one of the limb members and a portion of the body;

45 Fig. 6 is a horizontal sectional view on the line 6-6 of Fig. 3;

Fig. 7 is a view illustrating the sock from which the body and upper limb members of the doll are to be formed, the dotted 50 lines indicating the lines along which the sock is to be cut to provide the required blanks;

Fig. 8 is a group perspective view illustrating the sock after being cut along the 55 dotted lines in Fig. 7;

Fig. 9 is a perspective view illustrating one of the blanks partly finished;

Fig. 10 is a group perspective view illustrating the two upper limb members partly finished;

60 Fig. 11 is a view similar to Fig. 7 illustrating the other sock and the lines along which the same is to be cut to provide the necessary blanks;

Fig. 12 is a view similar to Fig. 8 illustrating the sock after being cut into the blanks;

Fig. 13 is a perspective view of the sleeve members of one of the articles of apparel partly completed;

70 Fig. 14 is a perspective view of the collar.

In manufacturing the doll, two socks, preferably of contrasting colors, will be selected, one of said socks being preferably 75 white in color and being the one from which the body and limb members of the doll are to be formed. This sock is illustrated in flattened out form in Fig. 7 of the drawings and is indicated in general by the numeral 80

1, and in preparing the sock for the manufacture of the doll, the same is to be cut along the dotted lines shown in the said figure. In thus cutting the sock several blanks will be produced, indicated one by 85 the numeral 2, another by the numeral 3, a third by the numeral 4, and a fourth by the numeral 5. The blank 2 constitutes the upper and heel portion of the sock, the blanks 3 and 4, respectively, the portions of the 90 sock which fit over the instep and the ball of the foot, and the blank 5 the toe portion of the sock. This latter portion is of no use in the present method and is therefore to be discarded as are also the relatively narrow 95 strip portions which are indicated in Fig. 7 of the drawings by the reference letter *a* and which are located between the portions which are to form the blanks 3 and 4. The upper or top portion of the sock is cut along 100 the dotted line shown in the upper portion of Fig. 7 so as to provide a longitudinally extending incision 6 providing integral portions 7 the ends of which are preferably cut to a more or less tapered form as indicated by the numeral 8. These portions 7 are to constitute the lower limbs of the doll and, as illustrated in Figs. 6 and 9 of the 105 drawings and indicated by the numeral 9, the edges of each portion are to be united 110

by stitching so as to form pockets which are to be filled by stuffing material indicated by the numeral 10, and which stuffing is preferably of cotton wadding, although any other soft material may be employed for the purpose if otherwise suitable. After having stitched together the edges of the portions 7 as above stated, the material 10 is to be stuffed into the blank 2 until it is sufficiently compact and completely fills the blank including the said leg portions 7. The material of the blank at its open end, which is indicated by the numeral 11, is then gathered and stitched so as to close the said blank. The slight bulge in the blank 2 which in the sock in its original condition constituted the heel of the sock, will now constitute the head of the body of the doll, the bulge being presented forwardly so as to form the face of the doll and being suitably lined or painted, as indicated by the numeral 12, so as to represent the facial features. In order to provide the body with a neck, the filled blank 2 is to be contracted between the head and trunk portions in a manner which will be presently pointed out.

In order to simulate feet at the lower ends of the limb members 7, cords or ribbons 13 may be tied more or less tightly about the said limb members 7 a suitable distance above their lower ends so as to circumferentially contract these members for the purpose stated.

In forming the upper limb members, the blanks 3 and 4 have their longitudinal edges brought together in each instance and stitched as indicated by the numeral 14, and as clearly shown in Fig. 10 of the drawings, whereupon one end of each tubular blank thus formed may be closed by stitching and the blanks filled with the stuffing material after which the other end is to be closed by stitching and finally the blanks are stitched to the body 2 at the shoulders so that they will then constitute the arms of the doll. In order to simulate hands at the lower ends of the arms, cord, tape, or ribbon indicated by the numeral 15 is to be tied more or less tightly about each of the arm members a suitable distance above its lower end so as to circumferentially contract the same in the same manner as previously explained with regard to the feet of the lower limb members.

55 The body and limb members of the doll having been thus produced from the blanks cut from the sock 1, the apparel for the doll is provided by cutting the other sock in a manner which will now be described.

60 The sock above referred to is indicated in general by the numeral 16 and the same is cut along the dotted lines shown in Fig. 11 of the drawings so as to form the blanks shown in Fig. 12, one of said blanks being indicated by the numeral 17, another by the

numeral 18, another by the numeral 19, and others by the numerals 20 and 21. As previously stated it is preferable that this sock be of some distinguishing color so that the articles of apparel formed from the several blanks will suitably contrast with the white body of the doll. The blank 17 which is formed from the upper portion of the sock 16, is fitted in inverted position over the body of the doll before the arms 70 are stitched in place and the upper edge of this blank is suitably stitched to the neck portion of the body of the doll as indicated by the numeral 22. The relatively coarse knit or rib portion of the blank, indicated by the numeral 23, may then be folded in the manner shown in Fig. 3 of the drawings and indicated by the numeral 24, so as to simulate the lower portion 80 of a sweater, these folds or rolls extending 85 circumferentially about the waist portion of the body of the doll. The blank 18 has no function in the present method and may, therefore, be discarded as well as the portions a' which correspond to the portions a 90 of the first described sock. Each of the blanks 20 and 21 has its longitudinal edges brought together and stitched as indicated by the numeral 25 and as clearly shown in Fig. 13 of the drawings, and in this manner the sleeves of the sweater are provided, the said sleeves being suitably stitched at their upper ends to the sweater or to the sweater and body of the doll, either as desired. The lower ends of the sleeves may be 100 suitably hemmed to prevent unraveling and to present a neat appearance.

The blank 19 which constituted the toe to the sock 16, may now be employed to serve as a cap for the doll, the same being preferably turned in at its lower edge and stitched, as indicated by the numeral 26, to the head of the doll. This cap may be provided at its apex with a suitable tassel indicated by the numeral 27 or it may be 110 left plain or supplied with any other suitable ornament. Fig. 14 of the drawings illustrates a collar which is indicated by the numeral 28 and which collar may be of linen or any other material possessing a suitable 115 degree of stiffness, and this collar is to be stitched in any suitable manner to the neck portion of the body of the doll and, if desired, by the stitches 22.

From the foregoing description of the 120 invention it will be seen that, without any considerable waste of material, I am enabled, by the method of the present invention, to cut from a pair of socks, blanks 125 which may be readily fashioned to form members of the body of the doll and articles of apparel for dressing the doll. If desired buttons 29 may be sewed onto the front of the sweater 17, and in fact the doll may be ornamented to any desired extent.

Having thus described the invention, what is claimed as new is:

1. The method of producing a doll from a sock which comprises cutting off the toe portion of the sock, cutting off the instep portion of the sock and longitudinally dividing the instep portion, slitting the normally top portion of the sock to provide limb blanks, uniting the edges of the said blanks to close their sides and lower ends, stuffing the blank, closing the end thereof at which the heel portion is located at a point beyond the said heel portion whereby the heel seat will constitute the face of the head member of the doll and the closed end of the blank will be located at the rear of the said head portion circumferentially restricting the body member to define the body and head portions of the doll, uniting the edges of the blanks resulting from the longitudinal division of the instep portion of the sock and stuffing the tubular blanks thus provided to form limb members, and uniting the limb members to the body member at the shoulder portions thereof.

2. The method of producing a doll from a sock which comprises cutting off the toe portion of the sock, cutting off the instep portion of the sock and longitudinally dividing the instep portion, slitting the normally top portion of the sock to provide limb blanks, uniting the edges of the said blanks to close their sides and lower ends, stuffing the blank, closing the end thereof at 30 which the heel portion is located at a point beyond the said heel portion whereby the heel seat will constitute the face of the head member of the doll and the closed end of the blank will be located at the rear of the said 35 head portion circumferentially restricting the body member to define the body and head portions of the doll, uniting the edges of the blanks resulting from the longitudinal division of the instep portion of the sock 40 and stuffing the tubular blanks thus provided to form limb members, and uniting the limb members to the body member at the shoulder portions thereof circumferentially restricting the limb members near their 45 lower ends to simulate feet or hands, as the case may be. 50

3. The method of producing a doll from a sock which comprises cutting off the toe portion of the sock, cutting off the instep portion of the sock and longitudinally dividing the instep portion, slitting the normally top portion of the sock to provide limb blanks, uniting the edges of the said blanks to close their sides and lower ends,

stuffing the blank, closing the end thereof at 60
which the heel portion is located at a point
beyond the said heel portion whereby the
heel seat will constitute the face of the head
member of the doll and the closed end of the
blank will be located at the rear of the said 65
head portion, uniting the edges of the blanks
resulting from the longitudinal division of
the instep portion of the sock and stuffing
the tubular blanks thus provided to form
limb members, and uniting the limb mem- 70
bers to the body member at the shoulder
portions thereof; and, producing apparel
for the doll from another sock by cutting
the sock to provide the toe portion, the upper
portion, and the instep portions, utilizing 75
the toe portion as a cap and utilizing the
upper portion as a body garment by fitting
the same onto the body of the doll with the
formerly upper end lowermost and leaving
said end unattached whereby it may be 80
rolled to simulate the roll of the sweater.

4. The method of producing a doll from a sock which comprises cutting off the toe portion of the sock, cutting off the instep portion of the sock and longitudinally dividing the instep portion, slitting the normally top portion of the sock to provide limb blanks, uniting the edges of the said blanks to close their sides and lower ends, stuffing the blank, closing the end thereof at which the heel portion is located at a point beyond the said heel portion whereby the heel seat will constitute the face of the head member of the doll and the closed end of the blank will be located at the rear of the said head portion, uniting the edges of the blanks resulting from the longitudinal division of the instep portion of the sock and stuffing the tubular blanks thus provided to form limb members, and uniting the limb members to the body member at the shoulder portions thereof; and, producing apparel for the doll from another sock by cutting the sock to provide the toe portion, the upper portion, and the instep portions, longitudinally dividing the instep portion to provide blanks, uniting the edges of said blanks to render the same of tubular form, and fitting the blanks onto the upper limb members to simulate sleeves, utilizing the toe portion as a cap and utilizing the upper portion as a body garment by fitting the same onto the body of the doll with the formerly upper end lowermost and leaving said end unattached whereby it may be rolled to simulate the roll of the sweater. 115

In testimony whereof I affix my signature.
MINNIE M. MELDRAM. [L. S.]
